UNITED STATES PATENT OFFICE

164,474

STORE BUILDING

William Alan Bryans, Denver, Colo.

Application May 6, 1950, Serial No. 9,753

Term of patent 14 years

(Cl. D13—1)

To all whom it may concern:

Be it known that I, William Alan Bryans, a citizen of the United States of America, residing at the city and county of Denver, State of Colorado, have invented a new, original, and ornamental Design for a Store Building, of which the following is a specification, reference being had to the accompanying drawing, forming part hereof.

Figure 1 is a front elevation of a store building showing my new design. Figure 2 is a cross sectional view taken along lines 2—2 of Figure 1; and Figure 3 is a vertical sectional view taken along lines 3—3 of Figure 1.

I claim:

The ornamental design for a store building, as shown.

WILLIAM ALAN BRYANS.
